FLEXIBLE STAYBOLT STRUCTURE

Julius Kindervater, Richmond, Va.

Application April 10, 1933, Serial No. 665,251

1 Claim. (Cl. 85—1.5)

This invention relates to a particular type of flexible staybolt structure, as will later more fully appear, and has for its primary object the devising of an improvement directed to increasing the life of a feature of the bolt and thereby increasing the life of the bolt itself, while maintaining the simplicity of the feature and the low cost of its manufacture.

The modern designs of flexible staybolts are usually provided with a tell-tale hole open at the inner end of the bolt and extending through the bolt into the head in one type of bolt, and entirely through the head and open at the outer end in another type of bolt. This invention relates to the last mentioned type of bolt.

A legal requirement is that boiler staybolts be inspected at designated periods. This is a costly procedure with all types of bolts, but much less costly with the type wherein the tell-tale hole extends entirely through the bolt from end to end. In this type of bolt all that is necessary as a preliminary step to making the hydraulic test required is to force a rod through the tell-tale hole to make sure that it is not obstructed.

In flexible staybolt structures the outer end of the bolt is provided with a head, and a sleeve is usually employed for supporting the head. In the present type of bolt the tell-tale hole is open at its outer end to the atmosphere, and a sealing flexible diaphragm or other element connects the outer end of the bolt with the sleeve to provide a steam-tight closure to prevent any steam or water that may enter the sleeve from passing to the exterior.

While the through tell-tale hole bolt is a superior type from the standpoint of economy of inspection, it nevertheless can easily be made a non-competitive type because of the cost of manufacture of the flexible element unless such cost can be reduced to a minimum. Therefore, it is highly desirable, if not absolutely necessary, to employ the simplest and consequently the cheapest type of flexible element, which, obviously, is that of general disc formation. It is comparatively easy to build up the cost of the flexible feature to an amount equal to or greater than the bolt itself, and no elaborate or complex type of flexible feature, such for instance as that shown in the Budwell Patent 1,603,579, is, for this reason, feasible.

An essential requirement of this type of staybolt is that it shall have a sufficiently long life to make it commercially practical. In service the bolt head and sleeve are subjected to frequent relative movements which include relative longitudinal movement as is well known, as well as universal movements provided for by the flexible jointure. These movements induce a corresponding flexure or distortion of the flexible element, and it has been found that the simpler forms of flexible ele-

ments are of shorter life than the more elaborate types such as that shown in the Budwell patent.

The problem therefore is to improve the simpler low cost diaphragm or disc-like structure so as to increase its life and thereby make it practical for use in the aforesaid type of staybolt having a tell-tale hole, open at the outer end. This invention is directed to an improvement of such flexible diaphragm element of substantial disc formation.

Referring to the drawing: Figure 1 is a central longitudinal sectional view of a staybolt structure embodying the present invention, secured to the boiler sheets fragmentally shown in section, the bolt being shown in elevation; Fig. 2 is a fragmental view, the left half being similar to the upper left half of Fig. 1, but showing the diaphragm-like sealing member in the process of being assembled, and the right half being an elevation; Fig. 3 is a plan view of the bolt; Fig. 4 is a plan view of the cap for the sleeve; and Fig. 5 is a central sectional elevation of the diaphragm.

The staybolt construction here chosen for illustrative purposes is similar to that of my co-pending application Serial No. 572,564, filed November 2, 1931, issued as Patent No. 1,909,108, May 16, 1933 and attention is invited to this co-pending application for a more complete detailed description of various of the parts. The present invention however is in no way restricted to any particular design, but is applicable to any design of this type of staybolt structure.

Referring more particularly to the several views, an open ended sleeve 1 is supported in an orifice in an outer sheet 2 of a boiler, to which it is secured, by welding, all in the usual manner. A bolt 3 having its inner end threaded, extends through the sleeve, projecting from the outer open end and extending from the inner open end, through the boiler, and is screwed into a threaded opening in an inner sheet 4 of the boiler, and headed over at the inner end, all in the usual manner. A head 5, provided with slots 6 for engagement by a tool to facilitate the assemblage of the bolt in the usual manner, is formed at the outer end portion of the bolt, and is provided with a face 7 supported upon a seat 8 provided within the sleeve, a flexible connection between the bolt and sleeve being thereby provided.

A tell-tale hole 9 extends throughout the entire length of the bolt. The upper end of the sleeve provides a transverse seat 10 for the sealing diaphragm, which is indicated generally by the reference A. The outer end of the bolt is threaded and contracted to form another transverse seat 11 for the diaphragm A. A cap 12 having a central orifice to permit the bolt to extend therethrough, is screwed on to the sleeve against the diaphragm to hold the diaphragm in steam-tight engagement

upon the seat 10. A backing 13 is mounted on the end of the bolt suitably spaced from the cap to permit the required relative movements, and is held tightly against the diaphragm by a nut 14, 5 screwed on the end of the bolt, to make a steam-tight joint between the bolt seat 11 and diaphragm. Obviously, if desired, the backing and nut may be formed as one piece.

The diaphragm is made of flexible non-rustable 10 sheet metal, and in the usual former practice, it is given a permanent shape more or less similar to that shown in Fig. 1. As this bolt in service moves relative to the sleeve, the permanently formed corrugation of the diaphragm is compelled to flex at the permanent bend or bends 15 forming the corrugation, and it has been observed that the diaphragm often first breaks down at a bend. It is well known that a permanent sharp bend in such flexible metal tends 20 to stiffen the metal at the bend making it less flexible and more liable to crack and these former types of diaphragms made from the usual grades of non-rustable flexible sheet metal have not proven of sufficiently long life to render this type 25 of bolt entirely satisfactory.

The diaphragm A of the present invention is made of resilient non-rustable sheet metal, such 30 for instance as a mixture containing brass, and is shaped during its manufacture substantially as shown in Figs. 2 and 5.

The diaphragm A has a central perforation or 35 opening 15 through which the outer threaded end of the bolt passes, and further comprises in its present preferred form, an outer horizontal sealing margin 16 having inner and outer peripheral edges 16a and 16b, respectively; an inner horizontal margin 17, spaced above the outer margin and having an inner peripheral edge 17a around the perforation 15 and an outer peripheral edge 17b; and a connecting wall 18 having 40 an outer peripheral edge 18a directly and integrally connected to the inner edge 16a of the outer margin and an inner peripheral edge 18b directly and integrally connected to the outer 45 edge 17b of the inner margin. The wall is preferably formed, as shown, somewhat converging upwardly.

The inner margin 17 comprises, around its inner edge 17a, a sealing portion 17c which is confined 50 between the seat 11 and backing 13, and around its outer edge 17b a spring portion 17d. This spring portion 17d and the wall 18 span the space which is provided in the bolt assemblage between the seats 10 and 11.

55 In assembling the parts of the staybolt structure the sleeve and bolt are assembled with and connected to the boiler sheet, as shown in Fig. 1. The diaphragm is then mounted on the outer end of the bolt and its margin 16 is disposed on 60 the seat 10 of the sleeve. The cap is then screwed into place to make a steam-tight joint, as shown in Fig. 2. The backing 13 is mounted on the end of the bolt in engagement with the sealing portion 17c of the inner margin 17 of the diaphragm, and 65 the nut 14 is screwed down upon the outer end of the bolt. The backing 13 is thereby gradually forced inwardly and the sealing portion 17c of the diaphragm is likewise gradually forced inwardly closer to the plane of the outer margin 16 70 until, in the preferred embodiment as shown, it is finally forced to its adjusted position upon its

seat 11 in the same plane with the outer margin 16 where it forms a steam-tight joint.

During this adjustment the spring portion 17d of the diaphragm margin 17 is constrained to place it under spring tension. During this adjustment this spring portion gradually assumes a natural temporary bend to spring energize it, and when in its final adjusted position it forms with the wall 18 a corrugation-like circular bulge, substantially as shown in Fig. 1.

10 It will be apparent that when the bolt moves relative to the sleeve under service conditions, the diaphragm will be correspondingly flexed to compensate for such movements, but will not act in the manner of the usual diaphragm of the permanent corrugation construction that has previously been referred to. With the diaphragm of the present invention there will be what will 15 more nearly approximate a purely spring action or movement with a minimum of cracking stress 20 at the angles. In short, the tensioned spring portion of the diaphragm of the present invention will alternately be slightly deenergized and reenergized during its different alternate movements from and to its normal position.

25 The improvement of the diaphragm as above set forth has been found to increase its life of service materially without increasing its cost of production, and has thus placed this type of staybolt on a competitive equality with the present 30 commonly employed flexible staybolt having the tell-tale hole closed at the outer end and which employs a closed cap for the sleeve instead of a diaphragm.

35 While there has been hereinbefore described a preferred embodiment of the present invention, it will be understood that many and various changes and modifications in form, structure and design may be made without departing from the spirit of the invention and that all such changes and 40 modifications are contemplated as a part of the present invention as defined in the appended claim.

The invention claimed and desired to be secured by Letters Patent is:

45 A boiler staybolt assemblage comprising a sleeve having a seat; a bolt having a head normally engaging said seat in flexible connection therewith; and a perforated resilient sealing diaphragm comprising an outer margin having an outer peripheral edge connected with said sleeve beyond said seat and an inner peripheral edge, an inner margin having an inner peripheral edge around the perforation secured to said head beyond the part thereof normally engaging said seat and an outer peripheral edge, said inner margin around its outer edge constituting a resilient flexible portion, flexed when said head is engaged with said seat to substantially frusto-conical ring shape energizing said diaphragm, said portion being deenergized and of relatively flat ring shape when unflexed, and a ring-shaped wall having an edge connected with the inner edge of said outer margin and extending angularly therefrom and having its opposite edge connected with the outer edge of said inner margin, said wall and flexible portion constituting a corrugation-like circular bulge when said flexible portion is flexed.

JULIUS KINDERVATER.
